UNITED STATES PATENT OFFICE.

EDWARD A. KNIERIEM, OF NEW YORK, N. Y.; GEORGE P. HOTALING EXECUTOR OF
SAID EDWARD A. KNIERIEM, DECEASED.

ABDOMINAL BANDAGE.

1,257,944.

Specification of Letters Patent. Patented Feb. 26, 1918.

Application filed October 11, 1915. Serial No. 55,299.

To all whom it may concern:

Be it known that I, EDWARD A. KNIERIEM, a citizen of the United States, residing at New York, in the county of New York and State of New York, have invented certain new and useful Improvements in Abdominal Bandages; and I do hereby declare the following to be a full, clear, and exact description of the invention, such as will enable others skilled in the art to which it app pertains to make and use the same.

This invention relates to abdominal bandages and it has for an object to provide such a bandage having the greatest range of adjustment to meet the requirements.

A further object of this invention is the provision of an abdominal bandage having stay strips formed therein which depend below the lower edge of said bandage to receive supporters, surgical bandages or sanitary bandages.

Further objects will be apparent from the following specification, appended claims and drawings thereof, in which—

25 Figure 1 is a perspective view of the bandage as applied to a wearer,

Fig. 2 is a similar view showing the rear side,

Fig. 3 is a plan view of the bandage detached,

Fig. 4 is a perspective view showing the bandage adapted for female wear,

Fig. 5 is a similar view showing the rear side of the bandage,

35 Fig. 6 is a perspective view of the bandage showing the same applied to a wearer in sitting position,

Fig. 7 is a detailed perspective view of a portion of the bandage, and

40 Fig. 8 is a perspective view of a modified form of adjusting means.

Referring to the drawings in which similar reference characters indicate similar parts, 10 indicates a plurality of elastic webs, of which each one has a fastener 11 attached to one end thereof as by the stitching 12 and the opposite end of each of said webs is provided with a link 13 as by the stitching 14. Each of the links 13 receives 45 a non-elastic web 15 which is bent upon itself to provide a section 16 which carries the adjusting buckle 17 to afford the desired adjustment of the webs 15. The opposite end of each of the webs 15 supports a co-acting 50 fastening member 18 and said web is folded 55

upon itself to present an extension 19 which is stitched to said web as at 20. The webs 10 support the vertical spacing members 21, 22 and 23 which are webs of non-elastic material folded as at 24 and stitched vertically 60 through the center thereof as at 25 to securely hold the webs 10 in the desired spaced relation and between each of the webs. These strips are stitched transversely 65 as at 26. A single row of vertical stitching, affords the desired flexibility of connection between the webs 10 and the spacing strips. The spacing strips are also stitched as at 27 below the lowest web 10 where the depending ends form tabs between which 70 fastening members 28 may be secured. The spacing strip 33 is provided with two fasteners 28 instead of a single one as shown on the strips 21, 22 and 23.

Intermediate of the spacing strips 21, 22 75 and 23 are the diagonally disposed suspender strips 29 which are attached as at 30 and 31 to the outer edges of the edge webs 10 and these suspender strips are stitched as at 32 between the web sections 10. These 80 strips will preferably be obliquely inclined with respect to the webs 10 and the pitch will be varied to suit the demands for different occasions. These strips also terminate below the lower edge of the webs 10 85 and between the tabs thus formed are similar fastening members 28.

The non-elastic webs 15 are held in spaced relation by a spacing strip 33 which is slidable on each of the webs 15 independently of 90 the others and this spacing strip is stitched as at 34 between the several webs as shown. The depending ends of this strip also form tabs and have fastening members 28 secured therebetween.

95 In use, this abdominal bandage is placed about the hips of a wearer in having the ends of the uppermost tab temporarily fastened to support said bandage, while the several parts thereof are being adjusted to the proper size. When the several tabs have been properly adjusted to establish the desired binding action, the spacing strip 33 will then be moved midway between the ends of the webs forming the back section and 100 the side strips 21 and 22 will be properly positioned over the hips of a wearer. After each of the fastening members 11 have been securely fastened to the corresponding members 18, and the bandage has been placed as 105 110

desired, the hose supporters or other corresponding bandages may be attached to the fastening members 28 and when they are adjusted to the desired degree of tension, it is apparent that these hose supporters or the like, prevent any upward movement of the bandage which may occur as the wearer moves his body, so it will be seen that between the waist encircling upper web of the 10 bandage and the hose supporters, this bandage will be held in the desired position. It is apparent that this bandage has an elastic front portion which overlies the fleshy portion of the abdomen of a wearer and the non- 15 elastic portion comprising the back section overlies the more or less solid portion of the back of the wearer, and that for different usages, different tensions may be placed upon the elastic strips to support and bind 20 the fleshy portions of the abdomen as desired.

In the formation of the bandage, the lowest of the elastic strips 10 will be either double or of an increased elasticity as shown 25 at 53 in Fig. 1 of the drawings.

Figs. 1 and 2 of the drawing, show the garment applied to a male figure and the fastening members 28 carried by the strips 21, 23 and 29 support co-acting fastening 30 members attached to the vertical elastic tapes 34 and the obliquely inclined tapes 35, which are provided with the usual adjusting buckles 36. At points above the knee of the wearer, the tapes 34 are provided with 35 cross tapes 37 of non-elastic material which are provided with the usual fastening means 38 and adjusting buckles 29 so that the desired contact of the leg of a wearer may be had without causing any binding or blood 40 pressure and from the junction of the tape 34 and cross section 37 depends the usual elastic garter 40 which may be provided with the adjusting buckle 41 and hosiery gripping devices 42. The tapes 37 hold the 45 hose supporter against derangement when the wearer assumes a sitting posture or the like.

Figs. 4, 5 and 6 of the drawings, show the bandage applied to a female figure and a 50 different type of hose supporter is substi-

tuted to that shown in Figs. 1 and 2 of the drawing.

The hose supporter in this instance comprises the vertical members 43 with adjusting buckles 44 and the diagonal members 45 with the adjusting buckles 46. The webs 43 are supported by fastening members attached to the lower ends of the webs 21 and 23 and the diagonal webs 45 are detachably carried by the lower ends of the webs 33. 55 Additional supporters 48 with adjusting buckles 49 are detachably carried by the lower ends of the webs 23. The elastic webs 43, 45 and 48 carry the usual grips 50 at the lower ends thereof. 60

Fig. 6 shows how the webs 10 overlap when the wearer assumes a crouched or sitting position. Fig. 7 shows the preferred form of co-acting fasteners for use on the vertical non-elastic webs and the appending 70 parts of garments. Fig. 8 shows an adjustment for each end of the non-elastic webs 15 in which a buckle 52 is carried by each of the folded ends 51.

Having thus described my invention, I 75 claim:—

1. In an abdominal bandage, a plurality of individual webs, forming front and rear sections, the webbing of said front sections being of elastic material to yieldably bind and support the abdomen of a wearer, and the webbing of said rear section being non-elastic to overlie the lower portion of the back of a wearer, said webs being held in spaced relation, and the lengths of the webs in said rear section being adjustable independently of each other. 85

2. In an abdominal bandage, a plurality of individual webs, spacing strips supporting said webs in spaced relation, some of said spacing strips having connection with said webs by a single row of vertical stitching to present flexibility, others of said spacing strips slidably supporting said webs, fastening means carried by said spacing strips, 90 and hose supporters pendant from the fasteners of some of said spacing strips to prevent upward movement of said bandage. 95

In testimony whereof I affix my signature.
EDW. A. KNIERIEM.
